UNITED STATES PATENT OFFICE.

FRANK E. BESSLER, OF AKRON, OHIO.

STAIRWAY.

Application filed January 17, 1923. Serial No. 613,272.

To all whom it may concern:

Be it known that I, FRANK E. BESSLER, a citizen of the United States, residing at Akron, in the county of Summit and State 5 of Ohio, have invented a new and useful Stairway, of which the following is a specification.

The device forming the subject matter of this application is of that general sort in 10 which a stairway is slidably mounted upon a panel, the panel being hinged to a ceiling, and the construction being such that the panel may be swung upwardly, and the stairway slid backwardly, thereby to dis- 15 pose the stairway in an out-of-the-way position, at the will of an operator.

The invention aims to provide novel means whereby the device may be mounted on ceiling frames of different heights, to 20 provide novel means for anchoring the cables, to provide novel means for operating the panel and the stairway, and, generally, to improve and to enhance the utility of devices of that type to which the invention 25 appertains.

With the above and other objects in view, which will appear as the description proceeds, the invention resides in the combination and arrangement of parts and in the 30 details of construction hereinafter described and claimed, it being understood that, within the scope of what is claimed, changes in the precise embodiment of the invention shown can be made without departing from 35 the spirit of the invention.

In the drawings:—

Figure 1 shows in elevation, a device constructed in accordance with the invention, the panel being lowered, and the stairway 40 being slid downwardly on the panel; Figure 2 is a fragmental transverse section taken through the supporting frame, through one of the stiles of the stairway and through attendant parts; Figure 3 is a horizontal 45 section taken through the structure shown in Figure 2; Figure 4 is a section of the structure shown in Figure 2; Figure 5 is a section on the line 5—5 of Figure 4, one of the stiles of the stairway appearing as an 50 added detail; Figure 6 is a fragmental vertical section taken through the upper portion of the stairway and attendant parts; Figure 7 is a sectional view wherein most parts appear in plan, the view depicting 55 the panel, the frame and parts at the upper end of the panel; Figure 8 is a ver-

tical section taken through the panel and attendant parts at a point adjacent to the lower end of the panel; Figure 9 is a perspective view disclosing the anchor which 60 is mounted on the stile of the stairway; Figure 10 is a sectional view depicting the spring-actuated drum; Figure 11 is a side elevation of the drum, parts being broken away.

The numeral 1 designates what for convenience may be denominated a frame, the numeral 2 designating the ceiling of a room, and the numeral 3 designating the floor of a room thereabove, joists 5 being interposed 70 between the ceiling and the floor and co-operating with the end portions of the frame 1, the ceiling 2 carrying a finishing strip 4 for the frame 1, the frame having an internal stop bead 6.

Hinges 7 are provided and carry the upper end of a vertically swinging panel 16 hereinafter alluded to. Each hinge 7 embodies a main plate 8 provided along its vertical edges with overhanging guides 9, the plate 8 being attached by securing elements 10 to one end of the frame 1. Each hinge 7 embodies an auxiliary plate 11 which, as shown in Figure 4 is provided at one end with an inner flange 12, the flange 12 being pivoted at 14 to the lower end of the main plate 8. Each hinge plate 11 has an outer flange 15 provided with an opening 18, the flanges 12 and 15 projecting in opposite directions. The auxiliary plates 11 of the hinges 7 extend along the upper surface of the panel 16 and are attached thereto by securing elements 17, as shown in Figure 7. The upper end of the panel 16 abuts against the flange 12 of the plate 11, as 85 shown in Figure 4. At its free end, the panel 16 is supplied with a latch 19, adapted to engage with the stop bead 6 or with a keeper of any other sort, when the panel 16 is swung upwardly, the latch 19 being under the control of a depending flexible element 20.

The numeral 21 marks a support in the form of a plate, the support being vertically slidable upon the main plate 8 of each hinge, 105 behind the guides 9, the support 21 being supplied at its upper end with a rearwardly extended lip 22 overhanging the upper edge of the frame 1 and held thereon by securing devices 23. The support 21, it will be observed, prevents the securing elements 10 from working their way out of the main

plate 8. The support 21 carries many important working parts of the device, as hereinafter described, and since the support 21 is vertically adjustable on the main plate 8, the fittings shown in Figure 2 may be adapted readily to the frames 1 having different heights.

The support 21 carries a forwardly extended bracket 24. A socket member 25 projects from the support and is disposed parallel to the bracket. The lower end of a post 26 is secured at 27 in each socket 25. A shaft 28 is mounted in the socket member 25 and in the bracket 24. A wheel 29 is journaled on the shaft 28 and is located between the bracket 24 and the socket member 25. An arm 30 is mounted to swing on the shaft 28 and is located between the wheel 29 and the socket member 25. The arm 30 has an inwardly extended stop flange 31, and is provided with an inwardly extended bottom flange 32, the flange 32 carrying an upstanding wing 33.

As shown in Figures 8 and 1, standards 34 are mounted on the panel 16 adjacent to the lower end of the panel, and are spaced apart transversely of the panel. The upper ends of the standards 33 are supplied with inwardly extended projections 35, which may be rollers. Struts 36 are mounted on the panel 16, between the upper and lower ends of the panel. Truss rods 37 are supplied. The lower ends of the truss rods are connected to the standards 34, the truss rods connecting with the struts 36. The upper ends of the truss rods 37 extend through the openings 18 in the flanges 15 of the hinge plates 11. Adjusting nuts 38 are mounted on the truss rods 37 and cooperate with the flanges 15, in a way which will be understood readily when Figure 6 of the drawings is examined. The truss rods, of course act as reinforcements for the panel 16.

A shaft 39 is carried by the standards 34, the shaft being of sufficient length so that the standards may be spaced apart at different distances, depending on the width of the panel 16. Bushings 40 are mounted on the shaft 39. The outer ends of the bushings 50 engage the standards 34. Retainers 41 are mounted in the shaft 39 and engage the inner ends of the bushings 40, to hold them in place. Wheels 42 are journaled on the bushings 40, the bushing having flanges 58, and the wheels 42 being disposed between the flanges 58 and the standards 34. The wheels 42 are supplied with outstanding peripheral flanges 43. Pulleys 44 are journaled on the shaft 39 and are located outwardly of the standards 34, retainers 45, such as cotter pins, being mounted in the shaft 39, outwardly of the pulleys 44.

The numeral 46 designates, generally, a stairway, including stiles 47 and treads 48, the uppermost tread being held in place by

angular binders 59. Posts 49 are mounted on the stairway 46 intermediate the ends thereof. Posts 50 are mounted on the stairway 46 adjacent to the lower end thereof. The post 26 carries a socket 51. There is a 70 socket 52 on the post 49. The post 50 has a socket 53. A hand rail 54 is located in the sockets 51, 52 and 53. The hand rail 54 is provided with a stop 55, which cooperating with the socket 51, limits the downward 75 movement of the hand rail. The hand rail is supplied with a stop 56 which, cooperating with the socket 53, limits the upward movement of the hand rail. Intermediate its ends, the hand rail 54 carries a projection 60. The operation of the hand rail need not be described in detail, because the hand rail is shown in several of my prior patents. Let it suffice to say, however, that when the stairway 46 is slid upwardly on 80 the panel 16, the hand rail 54 slides upwardly with the stairway through the socket 51 on the post 26 at the upper end of the stairway.

The stiles 47 of the stairway 46 are provided on their outer surfaces with longitudinal grooves 57. The stiles 47 of the stairway ride on the wheels 42 and are held thereon by the flanges 43 of the wheels as shown in Figure 8, the projections 35 on the standards 34 being received in the grooves 57 which are formed in the stiles 47 of the stairway. The stiles 47 of the stairway rest at their upper ends on the wheels 29 as shown in Figure 6. The upper flanges 31 of 100 the arms 30 are engaged in the grooves 57 of the stiles 47 of the stairway as shown in Figure 5, the bottom flanges of the arms extending beneath the stiles, and the wings 33 extending upwardly along the stiles.

Anchors 61, in the form of plates, are secured to the outer surfaces of the stiles 47 adjacent to the lower end of the stairway 46. A means for securing the anchors to the stiles is designated by the numeral 62. In one end of each anchor 61 a notch or seat 64 is fashioned, the notch or seat being aligned with the groove 57 in the stile 47. An opening 65 is formed in the anchor 61, and the material freed in the formation of this opening is extended inwardly to form a tongue 66 which, fitting in the groove 57, aids in supporting the anchor 61 on the stile. An opening 68 is formed in the anchor 61, and the material freed in the formation of this 110 opening is bent outwardly to form an arm 69 having a notch 70. When the notch 70 is formed, the material freed from the arm 69 remains attached to the anchor 61 and is extended outwardly to fashion a support 71.

Flexible elements 72 are provided. Intermediate their ends, the flexible elements 72 are wrapped about the pulleys 44, as shown at 73 in Figure 8, the flexible elements being extended downwardly along the stiles 120

47 of the stairway 46, the flexible elements being received in the notches 70 which are formed in the arms 69 of the anchors 61, the flexible elements passing across the outer ends of the supports 71, the flexible elements being received in the seat 64, and having knots or other enlargements which are received in the grooves 57 formed in the stiles 47 of the stairway 46. The parts 71 support the flexible elements 22 between the notches 70 and seats 64.

Bearing brackets 74 are mounted on the frame 1 and are shaped as at 75 to coact with the corner of the frame. The brackets 74 include standards 76 having bearing notches 77. The standards 76 are supplied with longitudinal lugs 78 having longitudinal grooves 79 communicating with transverse grooves 80 in the lugs. Shafts 85 are journaled in the bearing notches 77 of the standards 76. Cranks 81 are adjustable in the direction of their length, in the shafts 85 transversely of the shafts, the cranks 81 being supplied at their lower ends with projections 82. Drums 83 are mounted on the shafts 85. Peripheral springs 84 are located within the drums 83, the inner ends of the springs 84 being connected to the shafts 85, and the outer ends of the springs being connected to the drums 83. The upper ends of the flexible elements 72 are engaged with the drums 83. Ordinarily, the cranks 81 are engaged in the longitudinal grooves 79, the projections 82 of the cranks being received in the transverse grooves 80, the shafts 85 thus being held against rotation, and the springs 84 being so positioned that they will react upon the drums 83. When it is desired to adjust the tension in the springs 84, this may be done by rotating the cranks 81 until the projections 82 are disengaged from the transverse grooves 80, the cranks 81 being slid endwise, out of the longitudinal grooves 79, whereupon, by a proper manipulation of the cranks, rotation may be imparted to the shafts 85, thereby to adjust the tension in the springs 84, as aforesaid.

The general operation of devices of the kind hereinbefore described is well known and may be dismissed briefly, it being clear that the stairway 46 may be slid upwardly on the panel 16, the panel 16 being swung upwardly to a closed position, the flexible elements 72, responding to the action of the springs 84 in the drums 83 and aiding in the manipulation of the stairway.

Having thus described the invention, what is claimed is:—

1. In a device of the class described, a frame; a hinge plate secured to the frame and having guides; a panel; means for connecting the hinge plate to the panel; a support adjustable in the guides and provided

with a flange engaging the upper edge of the frame; a roller carried by the support; a stairway slidable on the roller; and means for supporting the stairway slidably on the panel.

2. In a device of the class described, a frame; a hinge plate secured to the frame and having guides; a panel; means for connecting the hinge plate to the panel; a support adjustable in the guides and having a flange engaging the upper edge of the frame; a roller journaled on the support; an arm mounted on the support; a stairway slidable on the roller and having a groove wherein a portion of the arm is slidably received; and means for supporting the stairway slidably on the panel.

3. In a device of the class described, a frame; a hinge plate secured to the frame and having guides; a panel; means for connecting the hinge plate to the panel; a support adjustable in the guides and having a flange engaging the upper edge of the frame; a roller journaled on the support; a socket carried by the support; a post engaged in the socket; a stairway slidable on the roller; means for supporting the stairway slidably on the panel; and a hand rail carried by the stairway and mounted slidably on the post.

4. In a device of the class described, a frame; a panel hinged to the frame; a stairway slidable on the panel and provided with a groove; means carried by the panel and engaged in the groove for guiding the stairway on the panel; an anchor on the stairway and provided in one end with a seat aligned with the groove, the anchor being provided intermediate its ends with an arm having a notch; a flexible element engaged in the seat and in the notch; means on the panel for guiding the intermediate portion of the flexible element; and lifting means assembled with the upper end of the flexible element.

5. A device of the class described, constructed as set forth in claim 4 and further characterized by the fact that the anchor is supplied with an inwardly projecting tongue received in the groove, the arm being struck from the anchor and the material freed in the formation of the notch in the arm remaining attached to the anchor to form a support, located between the seat and the notch in the arm.

In testimony that I claim the foregoing as my own, I have hereto affixed my signature in the presence of two witnesses.

FRANK E. BESSLER.

Witnesses:

RUTH N. VOLK,
O. J. SWINEHART.
